CLAIM

The ornamental design for a hose connector, as shown and described.

DESCRIPTION

FIG. 1 is a top front left perspective view of a hose connector according to a first embodiment;

FIG. 2 is a top rear left perspective view of the design of FIG. 1;

FIG. 3 is a front elevation view of the design of FIG. 1, the rear elevation view of the design of FIG. 1 being identical;

FIG. 4 is a top plan view of the design of FIG. 1;

FIG. 5 is a right side elevation view of the design of FIG. 1;

FIG. 6 is a left side elevation view of the design of FIG. 1;

FIG. 7 is a top front left perspective view of a hose connector according to a second embodiment;

FIG. 8 is a top rear left perspective view of the design of FIG. 7;

FIG. 9 is a front elevation view of the design of FIG. 7, the rear elevation view of the design of FIG. 7 being identical;

FIG. 10 is a top plan view of the design of FIG. 7;

FIG. 11 is a right side elevation view of the design of FIG. 7; and,

FIG. 12 is a left side elevation view of the design of FIG. 7. The dot-dash broken lines in the figures represent a boundary between claimed and unclaimed subject matter and form no part of the claimed design.

The dash-dash broken lines in the figures represent unclaimed subject matter and form no part of the claimed design.
